UNITED STATES PATENT OFFICE.

HENRY WEBER, OF CHICAGO, ILLINOIS, ASSIGNOR TO LATHAM MACHINERY COMPANY,
OF CHICAGO, ILLINOIS, A CORPORATION OF ILLINOIS.

WORK-GUIDE FOR STITCHING OR STAPLING MACHINES.

1,130,048.

Specification of Letters Patent.

Patented Mar. 2, 1915.

Application filed February 1, 1910. Serial No. 541,212.

To all whom it may concern:

Be it known that I, HENRY WEBER, a citizen of the United States, residing at Chicago, in the county of Cook and State of Illinois, have invented certain new and useful Improvements in Work-Guides for Stitching or Stapling Machines, of which the following is a specification.

This invention relates to improvements in work guides for stitching or stapling machines for directing and insuring the proper positioning of the work with respect to the stitching or stapling mechanism.

A further object is to provide an improved device of this character which will be simple, durable and cheap in construction, one which may be readily attached to the machine and as readily removed, and which will be effective and efficient in operation.

To the attainment of these ends and the accomplishment of other new and useful objects as will appear, the invention consists in the features of novelty in the construction, combination and arrangement of the several parts hereinafter more fully described and claimed and shown in the accompanying drawings illustrating an embodiment of the invention, and in which—

Figure 1 is a top plan view of an improved device of this character constructed in accordance with the principles of this invention and showing the same as applied to the work supporting table or arm of a stapling machine. Fig. 2 is a front elevation of Fig. 1. Fig. 3 is an enlarged detail view in elevation, showing the manner of attaching the work supporting table to the main support or arm. Fig. 4 is a sectional view on line 4—4 of Fig. 1. Fig. 5 is a detail sectional view on line 5—5 of Fig. 1. Fig. 6 is a detail sectional view on line 6—6 of Fig. 1, showing a box or casting in position to be stapled or stitched. Fig. 7 is a sectional view on line 7—7 of Fig. 1, showing a portion of the box or case in position.

Referring more particularly to the drawings and in the present exemplification of the invention, the numeral 10 designates the main support, to which is secured a work supporting arm or member 11. This arm or member 11 is adjusted laterally with respect to the support 10 by means of a suitable adjusting device 12, whereby the work-

ing support or arm may be positioned with respect to the stapling mechanism designated generally by the reference numeral 13 in Fig. 2.

All of the above mentioned parts may be of any desired construction and form no part of the present invention, but constitute the subject-matter of a separate application.

The work support or arm 11 is provided with a plurality of laterally projecting studs or bolts 14, which may be arranged in any desired position with respect to the length of the arm, and are adapted to be engaged by portions of brackets 15, which latter are provided with key-hole slots 16, through which the heads of the bolts 14 pass and are secured to platforms or table sections 17. These platforms or table supports are so arranged that when secured in position on the arm 11 by means of the bolts 14 their upper faces will stand substantially flush with the upper face or edge of the arm 11, so as to form an extended support or table for the work to rest upon. The table sections are provided with a plurality of bolt apertures 18, which are preferably formed in metallic strips 19, and these strips are countersunk in the upper faces of the table sections so that their upper faces will stand substantially flush with the top of the table sections. These strips 19 are preferably arranged parallel with the arm 11 and on each side thereof. Similar strips 20, 21 may be provided and countersunk in the face of the table sections and are arranged so as to extend across the table sections transversely with respect to the strips 19.

A gage 22 is provided with rearwardly projecting arms or portions 23, which latter are provided with slots 24, through which fastening devices 25 pass so as to engage the bolt apertures 18 in the strips 19. This gage 22 extends transversely with respect to the arm 11, and may be adjusted longitudinally with respect to the arm by loosening the fastening devices 25. After adjustment, the gage may be secured in its adjusted position by tightening the fastening devices. This gage is also preferably provided with a rearwardly projecting portion 26, which is grooved as at 27.

The work guide comprises a guide support 28, which is preferably in the form of an arm. One extremity of this arm is fas-

tened by means of a suitable fastening 29 in a recessed portion 30 of the work support 11, and the body portion 28 thereof is adapted to be seated in the groove or recess 27 in the gage 22. This guide support may be of any desired length, and the free end thereof is off-set or deflected laterally as at 31. The free extremity 32 of the off-set or laterally projecting portion 31 is again deflected as shown, so as to stand substantially parallel with the body portion of the guide support. The work guide support or arm and the deflected extremities 31 and 32 thereof are held in position in such a manner as to be spaced above the table, and secured to the free extremity 32 of the guide support is a guide 33 over and upon which the work passes and rests, provided with a flange 34 along one edge thereof to form a vertical guiding web. This guide 33 is arranged transversely with respect to the support 11 and substantially parallel with the gage 22 with the flange or wall 34 disposed in a direction toward the free end of the work support 11. The flange or wall 34 is deflected as at 35 to form a rounded portion, and the guide 33 is supported from the body portion 28 preferably by means of a plate or member 36, which is secured as at 37 to the flanged portion or wall 34 so as to be spaced above the guide, as shown more clearly in Fig. 6. The plate or member 36 is secured as at 38 to the extremity of the deflected portion 32 of the guide support or arm 28. The plate or member 36 is secured to the guide 33 at a point intermediate the extremities thereof and the flange or wall 34 terminates adjacent the end of the plate or member 36 at a point remote from the end 39 of the guide 33. The free extremity of the end 39 is provided with a clenching portion 40 for clenching the legs of the staple after it is inserted into the box or case.

By properly positioning the guide above the surface of the work support, it will be apparent that when the box or case 41 is placed upon the work support, its edges will be guided and properly positioned with respect to the stapling mechanism.

In use the box or case 41 (see Fig. 6) being folded in the usual manner, that is, so that the wall 42 thereof will fold under the wall 43, the box may then be placed upon the work support so that one edge will strike the gage 22, (the latter being first properly adjusted with respect to the guide 33.) When in position, the lowermost portion 41 of the box will rest upon the work support and the edge of the wall 42 will rest upon the guide 33, while the edge of the wall 43 will pass over the plate or member 36 as the box or case is fed to the stapling mechanism. With this improved construction it will be apparent that when the box or case is placed upon the work support, the edge

of the wall 42, or rather the corner thereof, will strike the rounded portion 35 of the vertical web 34, and during a further movement of the box or case toward the stapling mechanism the edge of the wall 42 will engage the wall or flange 34 and be guided thereby, at the same time shoving another end of the box or case against the gage 22. The edge of the wall 42 will then pass under the plate or member 36, and the edge of the wall 43 will pass over the plate or member 36. As the box or case is advanced to the stapling member, the faces of the walls 42 and 43 along their edges will rest against each other, as shown in Fig. 7, and will be positioned so that a staple or fastening device may be inserted through the overlapping portions at a point above the clenching portion 40 of the guide.

With this improved construction it will be apparent that the work will be properly positioned to insure the proper insertion of the staple through the overlapping portion.

Obviously when boxes or cases of varying sizes are to be fastened or stitched the gage 22 may be adjusted toward or away from the flange or wall 34 and the guide 33. It will also be apparent that when desired the table sections 17 may be readily detached and the guide may also be as readily detached.

In order that the invention might be fully understood, the details of the foregoing embodiment thereof have been thus specifically described.

I claim—

1. The combination with a work supporting arm arranged to support the portion of the work being operated upon, of a guide having one end thereof positioned over said work supporting arm at the point at which the work is operated upon, and a guide support offset at one terminal and attached to said guide at such offset terminal to properly position such guide and provide a clearance over the work-supporting arm adjacent to the terminal of said guide support.

2. In a machine of the character described, the combination of a work support, a work gage, a work guide independent of the gage, said guide being spaced from the gage, a portion of the guide being deflected away from the gage, said deflected portion being adapted to be engaged by one edge of the work to force another edge toward the gage by the movement of the work across the support.

3. The combination with a guide having a guiding web formed along one edge thereof, said web being deflected outwardly at one terminal, of a horizontal web secured to the edge of said guiding web, a guide support attached to said horizontal web, and a gage co-operating with the guiding web aforesaid for operation against the opposite edges of the work.

4. In a machine of the character described, the combination of a work support, a work gage, a work guide coöperating with the gage and adapted to be engaged by one edge of the work, means whereby work will be forced toward the gage by the engagement of the work with the guide, to position the work to receive a fastening device, and means supported by the guide for clenching the fastening device.
5. In a machine of the character described, the combination of a work support, a work gage, an elastically supported work guide coöperating with the gage and adapted to be engaged by one edge of the work, means whereby work will be forced toward the gage by the engagement of the work with the guide to position the work to receive a fastening device, and means supported by the guide for clenching the fastening device.
6. In a machine of the character described, the combination of a work support, a work gage, a work guide coöperating with the gage, means on the guide for separating the edges of overlapping portions of the work, one of the separated edges being adapted to engage the guide, means whereby the engagement of the said edge with the guide will force another edge of the work toward the gage to position the edges of the said overlapping portions of the work to receive a fastening device, and means for clenching the said fastening device.
7. In a machine of the character described, the combination of a work support, a work gage, a work guide coöperating with the gage, means on the guide for separating the edges of overlapping portions of the work, one of the separated edges being adapted to engage the guide, means whereby the engagement of the said edge with the guide will force another edge of the work toward the gage to position the edges of the said overlapping portions of the work to receive a fastening device, and means supported by the guide beyond the first said means for clenching the fastening device.
8. In a machine of the character described, the combination of a work support, a work gage, an elastically supported work guide coöperating with the gage and spaced from the support, said guide being adapted to extend between the folds of the work adjacent overlapping and coöperating edges, said guide being provided with a projecting portion adapted to be engaged by one of the said edges of the work, means whereby the engagement of the said edge with the said projecting portion will force another edge of the work toward the gage to position the work to receive a fastening device through the overlapping portions, and means supported by the guide for clenching the said fastening device.
9. In a machine of the character described, the combination of a work support, a work gage, an elastically supported work guide coöperating with the gage and spaced from the support, said guide being adapted to extend between the folds of the work adjacent overlapping and coöperating edges, said guide being provided with a projecting portion adapted to be engaged by one of the said edges of the work, the said projecting portion being provided with a deflected curved portion for directing the edge of the work toward the guide and for forcing another edge against the gage to position the work to receive a fastening device through the overlapping portions and means supported by the guide for clenching the said fastening device.
10. In a machine of the character described, the combination of a work gage, a work guide coöperating therewith, said guide comprising a body portion, provided with a flange projecting beyond the face thereof, a member supported by the flange and spaced from and extending over the body portion, said member terminating short of the forward end of the body portion, means for supporting the guide, said flange being adapted to be engaged by one edge of overlapping portions of the work, and said member passing between said portions and means whereby another edge of the work will be forced against the gage as the first said edge engages and moves toward the flange on the guide.
11. In a machine of the character described, the combination of a work gage, a work guide coöperating therewith, said guide comprising a body portion provided with a flange projecting beyond the face thereof, a member supported by the flange, spaced from and extending over the body portion, said member terminating short of the forward end of the body portion, a member to which the guide is secured for yieldingly supporting the guide, said flange being adapted to be engaged by one edge of the overlapping portions of the work, and said member passing between said portions, and means whereby another edge of the work will be forced toward the gage as the first said edge engages and moves against the flange on the guide.
12. In a machine of the character described, the combination of a work gage, a work guide coöperating therewith, said guide comprising a body having a portion shaped to form two members arranged in substantially parallel planes spaced from each other and connected along one edge with the open edge adjacent the gage, one of the spaced members projecting beyond each end of the other member, means on one of the said projecting ends for directing the edge of the work between the spaced mem-

bers and for forcing another edge toward the gage to position the work to receive a fastening device, and means for supporting said guide.

- 5 13. In a machine of the character described, the combination of a work gage, a work guide coöperating therewith, said guide comprising a body having a portion shaped to form two members arranged in 10 substantially parallel planes spaced from each other and connected along one edge with the open edge adjacent the gage, one of the spaced members projecting beyond each end of the other member, a flange on 15 one of the said projecting edges and extending beyond the face of the member, a portion of the flange being curved away from the open edge of the guide to be engaged by one edge of the work to direct 20 said edge between the members and to force another edge toward the gage, and means for supporting the guide, another edge of the work overlapping the first said edge and adapted to pass over the other of the said 25 spaced members.
14. In a machine of the character described, the combination of a work gage, a work guide coöperating therewith, said guide comprising a body having a portion 30 shaped to form two members arranged in substantially parallel planes spaced from each other and connected along one edge with the open edge adjacent the gage, one of the spaced members projecting beyond each end of the other member, means on one 35 each end of the other member, means on one

of the said projecting ends for directing the edge of the work between the spaced members and for forcing another edge toward the gage to position the work to receive a fastening device, means for supporting 40 said guide, and means supported by the other projecting end of the said member for clenching the fastening device.

15. In a machine of the character described, the combination of a work gage, a work guide coöperating therewith, said work guide comprising a body having a portion shaped to form two members arranged in substantially parallel planes spaced from each other and connected along 45 one edge with the open edge adjacent the gage, one of the spaced members projecting beyond each end of the other member, means on one of the said projecting ends for directing the edge of the work between 50 the spaced members and for forcing another edge toward the gage to position the work to receive a fastening device, means for yieldingly supporting the guide, and means on the other projecting end of the member 55 for clenching the fastening device.

In testimony whereof I have signed my name to this specification, in the presence of two subscribing witnesses, on this 26th day of January A. D. 1910.

HENRY WEBER.
